C. M. HANNAFORD

CAR DOOR MECHANISM

Filed May 2, 1924

Inventor

C. M. Hannaford

By Peltier & Meeklin
his attorney

UNITED STATES PATENT OFFICE.

CLEON M. HANNAFORD, OF RICHMOND, VIRGINIA, ASSIGNOR TO WINE RAILWAY APPLIANCE COMPANY, OF TOLEDO, OHIO, A CORPORATION OF OHIO.

CAR-DOOR MECHANISM.

Application filed May 2, 1924. Serial No. 710,593.

To all whom it may concern:

Be it known that I, CLEON M. HANNAFORD, a citizen of the United States, residing at Richmond, in the county of Henrico and State of Virginia, have invented certain new and useful Improvements in Car-Door Mechanism; and I do hereby declare the following to be a full, clear, and exact description of the invention, such as will enable others skilled in the art to which it appertains to make and use the same.

The invention relates to door locking and securing mechanism for railway dump cars and has for its principal object to provide a new and useful construction whereby a swingingly mounted door may be securely held in closed position.

Another object of my invention is to provide a swingingly mounted hopper car door with a reinforcing member, an end portion of which overlies the hopper side sheet and extends into the path of movement of the door securing hook.

A still further object of the invention is to provide a swingingly mounted hopper car door with a hook engaging member, said member having a portion which is interposed between the hook and the adjacent hopper side sheet, and another portion adapted to be releasably connected to said hook.

To these and other ends the invention comprises the various elements and combinations of elements hereinafter described, the novel features whereof will be pointed out in the claims.

In the drawings:

Figure 1 is a side elevational view of a portion of a hopper car showing a hopper side sheet and a swingingly mounted door and illustrating the invention.

Figure 2 is a view in elevation of the parts illustrated in Figure 1, the direction of view being at right angles to the direction of view of Figure 1.

Figure 3 is a cross sectional view on the lines 3—3 of Figures 1 and 2, the direction of view being indicated by the arrows adjacent the ends of said section lines.

Throughout the specification and drawings like parts are designated by like reference characters.

While I have illustrated but one hopper and the adjacent edge of the door, it will be readily understood by those skilled in the art

that the construction is preferably duplicated on the opposite side of the car and that the doors of each pair are located on opposite sides of the car center sills and are connected by a spreader or stiffening member so as to swing in unison. Such construction being so common in the art, it is not deemed essential to illustrate the same herein for a complete understanding of the invention.

The numeral 1 designates the sloping side sheet of a hopper, and 2 a swingingly mounted door adapted when in locked position to close the opening of the hopper. Said door is preferably provided with down-turned marginal flanges 3 and secured to the door in any desired manner is a stiffening member or spreader bar 4. The said spreader or stiffening member 4 may be of any commercial rolled section and is illustrated herein as of angle bar form having the flange 5 thereof secured to the lower face of the door 2 by a plurality of rivets or bolts 6 and having a flange 7 arranged substantially at right angles to the plane of the door 2. Adjacent the free edge of the door 2 one of the marginal flanges 3 is interrupted or cut away, as at 8, to permit the passage of the end portion 4^a of the spreader 4, said end portion being preferably bent at an angle to the door 2 so as to overlie and preferably to extend parallel with the side sheet 1 of the hopper.

Connected to the hopper side sheet 1 is a bracket 9 which may be provided with a plurality of perforated hubs 10, 11 and 12 through which the securing means or rivets 13 may extend. A door securing hook 14 is preferably pivotally mounted on the hub 12 by means of the rivet or fastening means 13 and pivotally secured to the hubs 10 and 11, also preferably by the rivets 13, are eccentric cams or dogs 15 and 16, the purpose of which will hereinafter be described.

At a suitable point in the flange 7 of the end portion 4^a of the spreader I provide a slot or recess 17 adapted to receive the bill 18 of the hook 14 so that the said hook when seated within said slot or recess will support the door 2 in closed position. The eccentric cams 15 and 16 are located on opposite sides of the hook 14 and the cam 15 is adapted to engage a portion of the shank of the hook 14 to prevent the disengagement thereof when in locked position. The

cam 16 is adapted to engage the outer face of the flange 7 to thereby prevent the bending of the portion 4^a of the spreader and to hold the door from longitudinal movement 5 in one direction. The engagement of the shank of the hook 14 with the opposite face of said flange and the engagement of the cam 15 with the hook 14 holds the door from movement in the opposite direction. It 10 will be observed that when the hook is in locked position the shank of the hook overlies the flange 5 of the portion 4^a of the spreader and hence prevents sliding movement of the door along the hinge pintles 15 thereof.

By providing a recess 17 in the flange 7 to receive the hook 14 all danger of the disengagement of the hook and door by weaving of the car underframe is avoided.

20 I claim:

1. The combination with a hopper, of a swinging door adapted to close the opening thereof, a member pivoted to the side sheet of said hopper, and means connected to said door and extending upwardly from the face thereof adapted to engage said pivoted member for maintaining said door in closed position.

2. The combination with a hopper, of a 30 swinging door adapted to close the opening thereof, a hook pivoted to the side sheet of said hopper, and means rigidly connected to said door and extending upwardly therefrom into the path of movement of said hook and engageable therewith for maintaining said door in closed position.

3. The combination with a hopper, of a 40 swinging door adapted to close the opening thereof, a bracket rigidly secured to the side sheet of said hopper, a hook pivotally connected to said bracket and adapted to swing in a plane parallel thereto, and a spreader member connected to said door, said spreader member having a portion 45 overlapping an edge of said door and extending upwardly therefrom and adapted to engage said hook for maintaining said door in closed position.

4. In a dump car, the combination with a 50 swinging door having flanges adjacent the free edges thereof, of a spreader member connected to the outer face of said door, one of said door flanges being cut away to form an opening therein, said member having a portion extending through said opening, and means rigidly connected to said portion and extending upwardly therefrom to engage means carried by said car for 55 releasably maintaining said door in closed position.

5. In a dump car, the combination with a 60 flanged door, of a reinforcing member therefor, said member comprising a flanged bar secured to the outer face of said door, one end of said member overlapping a free

edge of said door and extending upwardly therefrom, and means carried by said car for releasably engaging said flanged bar, said means being adapted to maintain said door in closed position.

6. The combination with a hopper, of a hingeably connected door adapted to close the opening thereof, means movably mounted on the side sheet of said hopper, and means rigidly connected to said door intermediate a free edge and said hinge and adapted to engage said movable means for releasably maintaining said door in closed position, said rigidly connected means being adapted to overlie the side sheet of said 70 hopper.

7. The combination with a hopper, of a swinging door adapted to close the opening thereof, said door having downturned marginal flanges along the free edges thereof, one of said flanges having a portion thereof removed to form an opening therein, a flanged member extending through said opening and having a portion thereof arranged parallel to the adjacent wall of said 85 hopper, and means mounted on said hopper wall for releasably engaging said flanged member for maintaining said door in closed position.

8. The combination with a hopper, of a swinging door adapted to close the opening thereof, of a bracket rigidly mounted on the side sheet of said hopper, an angle bar connected to the outer face of said door, a portion of said angle bar projecting beyond a free edge of said door, said projecting portion extending substantially parallel to and overlying said hopper sheet, means mounted on said bracket for engaging the projecting portion of said angle bar, and means pivotally connected to said bracket for maintaining said first named means in engaging position.

9. The combination with a hopper, of a swinging door adapted to close the opening thereof, said door having rigidly connected thereto an angle bar, a portion of said bar extending beyond a free edge of said door and adapted to overlie the adjacent side sheet of said hopper, a door locking member movably mounted on said hopper side sheet and adapted when in door locking position to overlie a flange of said angle bar, and movable means for engaging the other flange of said angle bar adjacent said door locking member.

10. The combination with a hopper, of a swinging door adapted to close the opening thereof, said door having rigidly connected thereto an angle bar, a portion of said bar extending beyond a free edge of said door and adapted to overlie the adjacent side sheet of said hopper, a door locking member movably mounted on said hopper side sheet and adapted when in door locking position 110 115 120 125 130

to overlie a flange of said bar, movable means for engaging the other flange of said angle bar adjacent said door locking member, and means for maintaining said door locking member in locking position.

11. The combination with a hopper, of a swinging door adapted to close the opening thereof, an angle bar spreader having one flange thereof lying parallel with and connected to the outer face of said door, a portion of said angle bar extending outwardly beyond and overlapping a side sheet of said hopper, a flange of said overflapping por-

tion of said angle bar having an opening formed therein, a hook pivotally mounted on said hopper side sheet, the bill of said hook being adapted to enter said opening for releasably maintaining said door in closed position, and movable means arranged on opposite sides of said hook for normally preventing relative movement between said hook and angle bar.

In testimony whereof I affix my signature.

CLEON M. HANNAFORD.
